Specification for Design.

Patented Mar. 29, 1921.

Application filed June 12, 1920. Serial No. 388,645. Term of patent 3½ years.

To all whom it may concern:

Be it known that I, FREDERICK A. FRERICHS, a citizen of the United States, residing at Philadelphia, in the county of Philadelphia and State of Pennsylvania, have invented a new, original, and ornamental Design for an Electric-Candle Chandelier, of which the following is a specification, reference being had to the accompanying drawing, forming part thereof.

The figure is a perspective view of an electric candle chandelier, showing my new design.

I claim—

The ornamental design for an electric candle chandelier, as shown.

FREDERICK A. FRERICHS.
